[57] CLAIM

The ornamental design for a shovel, as shown and described.

DESCRIPTION

FIG. 1 is a side elevational view, taken from the right side of FIG. 2, it being understood that the opposite side view is a mirror image thereof;

FIG. 2 is a front elevational view, taken from the left side of FIG. 1;

FIG. 3 is a rear elevational view thereof, from the right side of the shovel illustrated in FIG. 1;

FIG. 4 is a top plan view of the shovel illustrated in FIG. 1; and,

FIG. 5 is a bottom plan view of the shovel illustrated in FIG. 1.
